UNITED STATES PATENT OFFICE.

MAX SOBLIK, OF DRESDEN-KLOTZSCHE, GERMANY, ASSIGNOR TO SOBLIK SCHREIB-MASCHINEN GESELLSCHAFT MIT BESCHRAENKTER HAFTUNG, OF DUSSELDORF, GERMANY, A CORPORATION OF GERMANY.

PNEUMATIC TYPE-WRITER.

1,075,512.

Specification of Letters Patent. Patented Oct. 14, 1913.

Application filed February 18, 1913. Serial No. 749,082.

To all whom it may concern:

Be it known that I, MAX SOBLIK, a subject of the German Emperor, and residing at 2 Gartenstrasse, Dresden-Klotzsche, Kingdom of Saxony, Germany, have invented 5 certain new and useful Improvements in Pneumatic Type-writers, of which the following is a specification.

The present invention relates to type-writers in which the types are set and 10 printed by means of compressed air. Hitherto in typewriters of this kind known this was done by more or less complicated means.

It is the object of the present invention to 15 simplify this kind of typewriter and its operations.

Two compressed air or pneumatic motors are provided both of which are fitted with 20 a controlling gear and of which the one motor will effect the setting of the types and the other motor the printing of said set types.

Figure 1 is a longitudinal section of the 25 typewriter showing the working parts. Fig. 2 is a top plan of the interior mechanism of the machine. Fig. 3 is a sectional view of the controlling device for the motor serving to print the type wheel against the paper. Fig. 4 is an enlarged cross section through 30 shaft 1, taken directly below arm 10.

The shaft 1 of the motor 2 is shown to be 35 coupled by means of a flexible shaft 3, to the type wheel 4. As long as it has not been arrested, the said type wheel will be continuously revolved by the motor in the same direction. The shaft 1 of the motor 2 simultaneously forms the controlling device for the motor 5, which prints the types. On the other hand the shaft of the pneumatic motor 40 5 serves as a controlling member for starting the motor 2 after each adjustment. The alternate arresting and releasing of the two motors is effected by the exciting of two diaphragms provided on casings 6 and 7. 45 The motor 2 is surrounded by abutments 9 having the form of levers and being arranged in a circle around said motor. These abutments are each coupled to one of the keys, not shown, in such a manner, that 50 when one of said keys is depressed, the respective abutment will rise, so that it clears the pawl 8, which is under action of a spring and is supported by the same. The thus raised abutment now lies in the path of an 55 arm 10 revolving on the shaft 1 and arrests

its further rotation and thereby also the rotation of the motor 2 and of the type wheel 4, which will therefore revolve only so far as the raised abutment will admit. Before the rotation of the shaft is completed, the 60 valve 11 is opened, and the compressed air supplied through pipe 12 will enter into the pipe 13, which communicates with the diaphragm casing 6. In consequence thereof the diaphragm and with it the arm 14^a coupled with a pawl 14 is lifted. The pawl 14 will be so turned, that it releases an arm 15 coupled to the shaft 29 of motor 5, so that the motor 5 will make one revolution. In consequence thereof the crank pin 16 fitted 65 on the arm 15 will be revolved, and by this means and the co-operation of the rod 17 the type barrel 4 will be pressed against the platen 18, so that the type directed or pointed toward said platen is printed on the 70 paper thereon, whereupon the type barrel 75 will return into its initial position.

As hereinbefore said, the shaft of motor 5 is made to serve as a controlling member, by means of which the air supply pipe 19 80 communicating with the shaft housing is intermittently made to communicate with the pipe 20 and the latter with the exhaust 30. The pipe 20 communicates with an annular passage 21 in the housing 31, and through 85 this passage it communicates with a passage 23 in the shaft 1 of the motor 2 and in a rigid arm 22 attached to the same. On the arm 22 is fitted the diaphragm casing 7 in which the air can enter. The pneumatic 90 pressure will by means of the diaphragm 7 press the lever 8^a downward, so that the pawl 8 releases the abutment, which will under action of spring 24 move down again. In consequence thereof also the arm 10 is 95 again free and the motor 2 can again revolve.

The arrangement for sending a current of air through the shaft 1 into the pipe 13 is 100 not claimed under this application. It will however be here explained for clearness' sake. As above explained, arm 10 is free to turn on shaft 1, and is provided with a tap-pet 27 that is adapted to operatively engage the stem 11^a of valve 11. The latter controls 105 passage 26 and is carried by an arm 25 fast on shaft 1, which also carries a relatively fixed finger 25^a. Passage 26 communicates with the air supply pipe 12, and also with the pipe 13 leading to the diaphragm-casing 110

6. A spring 28 interposed between finger 25^a and arm 10 tends to hold the latter in such a position that tappet 27 is out of engagement with stem 11^a. During operation, 5 shaft 1 turns in a direction opposite to that of a clock hand, so that the relatively fixed finger 25^a will take along arm 10 and tappet 27 by means of spring 28. When arm 10 engages a raised abutment 9, its rotation is 10 instantly checked while the parts 25, 11, 11^a continue to rotate so that stem 11^a abuts against fixed tappet 27. In consequence thereof the said valve stem will be forced back and the air passages 12 and 13 which 15 had been interrupted by the closed valve will be open, so that the air can suddenly enter into the casing 6 and release the motor 5, and print the type wheel, the position of which will depend on the abutment which 20 has been raised.

I claim:

1. In a pneumatic typewriter, a platen, a first pneumatic motor, a type barrel adapted to be rotated thereby, a second pneumatic 25 motor adapted to move said barrel toward the platen, a plurality of abutments surrounding the first motor, pawls adapted to engage the abutments and sustain them in their raised position, means controlled by the abutments for arresting the first motor, and pneumatic means controlled by the second motor for tilting the pawls and thereby releasing the abutments.
2. In a pneumatic typewriter, a platen, a first pneumatic motor, a type barrel adapted to be rotated thereby, a second pneumatic motor adapted to move said barrel toward the platen, a valve operatively connected to the first motor, a movable member controlled by said valve, and means actuated by said movable member for controlling the second motor.
3. In a pneumatic typewriter, a platen, a first pneumatic motor, a type barrel adapted to be rotated thereby, a second pneumatic 30 motor, adapted to move said barrel toward the platen, a valve operatively connected to the first motor, a movable member controlled by said valve, and means actuated by said movable member for controlling the second motor.
4. In a pneumatic typewriter, a platen, a first pneumatic motor, a type barrel adapted to be rotated thereby, a second pneumatic motor, adapted to move said barrel toward the platen, a valve operatively connected to the first motor, a movable member controlled by said valve, and means actuated by said movable member for controlling the second motor, and means controlled by the second motor for tilting the pawls and thereby releasing the abutments.

the first motor, a first movable member controlled by said valve, means actuated by said first movable member for controlling the second motor, a second movable member, 45 controlled by the second motor, and means actuated by said second movable member for controlling the first motor.

4. In a pneumatic typewriter, a platen, a first pneumatic motor, a type barrel adapted to be rotated thereby, a second pneumatic motor adapted to move said barrel toward the platen, a plurality of abutments surrounding the first motor, pawls adapted to engage the abutments and sustain them in their raised position, means controlled by the abutments for arresting the first motor, and pneumatic means controlled by the second motor for tilting the pawls and thereby releasing the abutments. 50

5. In a pneumatic typewriter, a platen, a first pneumatic motor, a type barrel adapted to be rotated thereby, a second pneumatic motor adapted to move said barrel toward the platen, a plurality of abutments surrounding the first motor, pawls engaging the abutments, means coacting with the abutments for arresting the first motor, a valve operatively connected to the first motor, a movable member controlled by said valve, means actuated by said movable member for controlling the second motor, and means controlled by the second motor for tilting the pawls and thereby releasing the abutments. 55

In testimony whereof I have hereunto set my signature in the presence of two witnesses.

MAX SOBLIK.
